ADVERTISING DISPLAY

James L. D. Morrison, Benton Harbor, Mich.

Application May 26, 1951, Serial No. 15,322

Term of patent 3½ years

(Cl. D1—2)

To all whom it may concern:

Be it known that I, James L. D. Morrison, a citizen of the United States, residing at 270 Bradford Drive, Benton Harbor, in the county of Berrien and State of Michigan, have invented a new, original, and ornamental Design for an Advertising Display, of which the following is a specification, reference being had to the accompanying drawings, forming part thereof.

I claim:

The ornamental design for an advertising display, as shown.

J. L. D. MORRISON.
